UNITED STATES PATENT OFFICE.

ABNER H. WIBORG, OF BUFFALO, NEW YORK.

PUMP.

Application filed April 14, 1922. Serial No. 552,822.

To all whom it may concern:

Be it known that ABNER H. WIBORG, a citizen of the United States of America, residing at Buffalo, in the county of Erie and 5 State of New York, has invented new and useful Improvements in Pumps, of which the following is a specification.

The object of the invention is to provide an efficient construction of pump particularly for use in connection with oil and similar wells whereby the inconveniences incident to the back pressure of the liquid particularly when the pump is not in operation, and the dropping of any sand or sediment from the upper portion of the tubing into the working barrel may be prevented; and in that connection to provide a construction and arrangement of check whereby replacement may readily be effected, and to 10 provide a construction of working valve which also facilitates replacement and the maintenance of the valve seat in proper operative condition; and with these objects in view the invention consists in a construction 15 and combination of parts of which a preferred embodiment is shown in the accompanying drawings, wherein:—

Figure 1 is a side view partly in section of a pump mechanism embodying the invention.

Figure 2 is an enlarged detail sectional view of the piston.

Figure 3 is a similar view of the foot valve.

Figures 4 and 5 are detail sectional views respectively of the members of the check device.

In the illustrated embodiment of the invention the working barrel 10 is fitted with 40 a piston 11 having a cap 12 which carries the valve cage 13 suitably perforated or provided with outlet openings and adapted to retain the spherical or ball valve 14 in proper relation with its seat. For the reception of the valve there is provided a double seated ring 15 reversible to arrange either of the oppositely disposed seats 16 in position to cooperate with the valve and having an annular peripheral rim 17 engaged 45 between a shoulder 18 of the cap and the end of the working barrel 11, whereby it is firmly clamped and held in position. The pump rod 19 is connected by a suitable coupling 20 with the cage or cap 13 and arranged at the bottom of the working barrel and connected with the suction pipe 21 is

a foot valve casing 22 consisting of the collar 23 and the cap 24 forming a suitable valve cage for the spherical valve 25'. The valve cooperates as described in relation to the operating valve with a double faced seating ring 25 having a rim 26 which is clamped between a shoulder 27 of the cap 24 and the end of the collar 23 in a manner similar to that described with relation to the working 60 valve mechanism.

Located in a sleeve 28 fitted to the upper end of the working barrel is a checking device consisting of a collar or seating member 29 having threaded engagement at its lower 70 end with the upper end of the working barrel and a disk or valve member 30 loosely fitted upon the pump rod 19 and free to move on said rod between the upper end of the seating member and a stop formed by 75 inwardly directed lugs 31 on the sleeve 28. The seating member is provided with passages or channels 32 to permit of the passage of liquid therethrough and the disk member is of less diameter than the interior of the 80 sleeve to permit of the passage of fluid around the periphery thereof, said disk member having an annular cavity 33 in its upper face, serving to catch any particles of sand which may settle through the liquid 85 which remains in the pump tubing above the disk when the operation of the pump ceases, and prevent the dropping of the same into the working barrel where it is subject to lodgment between the piston and the wall 90 of the barrel and hence to an injurious scratching of either the piston or the barrel.

The rod 19 has reciprocatory sliding movement with relation to the seating member 29 when the pump is in operation. The valve 95 member 30 has sliding movement upon the rod 19 during the operation of the pump but the sliding movement of the valve member 30 is limited by the seating member 29 and the lugs 31. Therefore, the rod 19 may 100 reciprocate with longer strokes of reciprocation than the corresponding movement of the valve member 30. The lugs 31 prevent the valve member 30 from moving too far away from the seating member to prevent 105 the said valve member from seating promptly upon said member 29 during the relatively long strokes of reciprocation of the rod 19. In other words, the presence of the valve member 30 upon the rod 19 does not limit 110 the movement of the rod in that the movement of the valve member 30 which is slid-

ably mounted upon the rod is limited by the fixed stops and the adjustable seating member.

The detachability of the sleeve 28 from the working barrel permits of the cleaning or replacement of the check device should there be an objectionable accumulation of solid material adjacent thereto, and as will be obvious when the operation of the piston is discontinued the disk member of the check device will drop into contact with and will seat upon the upper end of the seating member and thus entirely cut off communication between the pump tubing and the working barrel.

Having described the invention, what is claimed as new and useful is:—

A pump comprising a working barrel, a rod mounted therein and carrying a working

valve, a sleeve threaded upon the upper end of the barrel and slidably receiving the rod, a seating member threaded within the upper end of the barrel and having a portion disposed above the upper end edge of the barrel, a piston rod slidably received in the seating member, a disk slidably mounted upon the piston rod and housed within the sleeve, stops carried by the sleeve and spaced above the seating member and disposed in the path of movement of the disk, said disk being provided at its upper side with an annular cavity, the parts being so arranged that the piston rod may have unlimited sliding movement with relation to the disk.

In testimony whereof he affixes his signature. 35

ABNER H. WIBORG.
